UNITED STATES PATENT OFFICE.

HENRY HORAN, OF EAST ORANGE, NEW JERSEY, ASSIGNOR TO THE LOWELL MANUFACTURING COMPANY, OF MASSACHUSETTS.

DESIGN FOR CARPET.

SPECIFICATION forming part of Design No. 24,647, dated August 27, 1895.

Application filed July 30, 1895. Serial No. 557,637. Term of patent 3½ years.

To all whom it may concern:

Be it known that I, HENRY HORAN, a citizen of the United States, and a resident of East Orange, in the county of Essex, State of New Jersey, have invented a new and original Design for Carpets and Borders, of which the following is a specification.

This invention comprises two parts—namely, the design A for carpet and the design B for border; and I do hereby declare that the drawing accompanying this specification conveys to any one a clear understanding of the same, and is sufficient to enable such person to use my invention.

15 The design A is characterized by clusters of small leaf and flower forms constituting its leading feature.

The design B is characterized by clusters of small leaf and flower forms with an outer border of festoons of small leaf and flower forms 20 constituting its leading feature.

What I claim, and desire to secure by Letters Patent, is—

1. In a design for carpet, the body A, substantially as shown.

2. In a design for carpet, the border B, substantially as shown.

3. The design for carpet, comprising the body A and the border B, substantially as shown.

25 In testimony whereof I have signed my name to this specification in the presence of two subscribing witnesses.

HENRY HORAN.
